UNITED STATES PATENT OFFICE.

MICHAEL GILSON, OF PORT WASHINGTON, WISCONSIN, ASSIGNOR TO KWIK-MIX
CONCRETE MIXER CO., OF PORT WASHINGTON, WISCONSIN.

AUTOMATIC LOCK AND RELEASE FOR CONCRETE MIXERS.

Application filed April 14, 1927. Serial No. 183,704.

This invention relates to concrete mixers. In concrete mixers as heretofore constructed, it has been the usual practice to provide some form of manually releasable latch so that after the operator judges the mixture to be substantially thoroughly mixed he releases the latch and tilts the mixing drum into charge dumping position. It is apparent that the judgment of the operator is not always exact and, consequently, mixtures having different characteristics are produced by this method with consequently varying results in the resulting concrete.

This invention is designed to provide an automatic release which normally maintains the mixing drum in latched position as it receives a charge, and which requires the mixing drum to execute a predetermined number of revolutions before the latch is automatically released, thus dispensing with the variable or uncertain judgment of the operator and insuring a uniform mixture at all times.

Further objects are to provide an automatic latching mechanism which does not begin to function until the drum is changed, but which is thrown into operation preferably by the charging bucket and thus commences to count or register the number of turns of the drum so that after a predetermined number of turns from the time the bucket receives the charge the latch is lifted.

Further objects are to provide a device which is eminently practical, which may be easily produced, and which is substantially fool-proof.

An embodiment of the invention is shown in the accompanying drawings in which:

Figure 1 is a side elevation with parts broken away showing a concrete mixer with the counting automatic mechanism in place showing in full lines the position of the parts during charging, and in dotted lines the position of the bucket after charging;

Figure 2 is a view partly in section looking down upon the mixing drum and the counting or automatic mechanism with other portions of the apparatus omitted for the sake of clearness;

Figure 3 is a vertical sectional view through the automatic mechanism housing showing the parts in their relative position and some in section, such view corresponding to a section on the line 3-3 of Figure 5;

Figure 4 is a view from the other side of the apparatus showing the other portion of

the casing in section, such view corresponding to a section on the line 4-4 of Figure 5;

Figure 5 is a transverse sectional view on the line 5-5 of Figure 3.

Referring to the drawings, it will be seen that a concrete mixer has been illustrated as of the portable type, although other forms may be used. The mixer comprises a framework 1 supported by transverse axles 2 carrying wheels 3. The frame provides bearings 4 for a pair of outwardly projecting trunnions 5 formed on the supporting yoke 5. The yoke 5 carries the mixing drum 6 in the usual manner and one of the trunnions 4 is apertured and carries the driving shaft 7 which is geared in the usual manner to the mixing drum and, consequently, is designed to rotate such drum. The other trunnion may be in the form of a shaft 8 and rigidly carries a latching plate 9. Further, this shaft or trunnion 75 also rigidly carries the gear 10 which is ordinarily used for dumping and may mesh with a small pinion in the usual manner, such pinion being omitted as it is merely conventional construction. The latching disc or 80 plate 9 is provided with a notch 11 into which a latch 12 is adapted to drop when the parts are in the position shown in Figure 1. Further, in connection with Figures 1 and 2 attention is called to the fact that the drum 85 is provided at any suitable point with a cam member 13 for a purpose hereinafter to appear. Also, suitable conventional mechanism, such, for example, as the cable 14, is provided for elevating the charging bucket 90 15 into charging position.

The automatic mechanism is carried within a housing 16 (see Figure 5) which is provided with an outer wall 17 and an inner wall 18. This housing also is provided with an intermediate or main wall 19 which supports the mechanism. This intermediate wall is also preferably provided with a laterally turned base 20 adapted for attachment to any suitable portion of the framework 1.

It will be seen therefore that the housing is divided into two compartments 21 and 22. Within the compartment 22, a rock arm 23 is positioned and is carried by a shaft 24 rigid therewith and pivotally supported in and extending through the wall 19, as shown in Figures 4 and 5. This rock arm 23 is spring urged in one direction by means of the spring 25. It is adapted to be rocked in the other direction by means of a reciprocating plunger 110

26 carried in suitable guides 27 (see Figure 4) secured to the wall 19. The plunger 26 projects outwardly from the housing and is provided with a roller 28 at its outer end adapted to be struck by the cam 13 once for each revolution of the mixing drum, thus imparting one rocking motion to the shaft 24 for each revolution of the mixing drum.

The shaft 24, as stated, extends through the partition or wall 19 and carries at its outer end a short lever 29 which is provided at its outer end with a pawl 30. The lever 29 is also provided with an apertured ear 31 (see Figure 3) through which a connecting rod 32 extends for a purpose hereinafter to appear, the connecting rod, it being noted, being loose within the ear 31 and provided with an enlarged head 33 at its upper end.

The pawl 30 operates upon a ratchet wheel 34 (see Figure 3) which is revolvably carried by a stub shaft 35 rigid with the wall 19. This ratchet wheel is rigid with a cam 36 which is provided with a high point followed by an abrupt radial face. The ratchet wheel 34 is preferably locked against inadvertent rearward motion by means of a spring urged latch or pawl 37.

The cam 36 controls the motion of the lever 38, one end of which constitutes a cam-follower and directly contacts with the cam as the cam rotates. The lever or rocking bar 38 is spring urged against the action of the cam by means of the elongated helical spring 39' (see Figure 3). It is adapted to control the latch tripping mechanism by means hereinafter to appear.

It is to be noted from Figure 3 that the lever 38 is rigid with the shaft 39 and that such shaft projects outwardly through the outer wall 17 of the housing, as shown in Figure 5. This shaft 39 carries adjacent its outer end a tripping arm 40 (see Figure 1) whose free end strikes a projecting portion 12' of the latch 12 and thus raises the latch 12 from the notch 11 when the lever 38 or rocking member rocks in a clockwise direction, as shown in Figure 3.

Thus, from the mechanism thus far described, it is apparent that when the cam 36 executes one complete revolution that the lever 38 will drop into the cutaway portion of the cam and will, consequently, rock in a clockwise direction, as viewed in Figure 3, thus releasing the catch 12 and permitting dumping of the mixing drum.

Further, it is to be noted that when this occurs that the connecting link 32 which is pivotally carried by the lever 38 (see Figure 3) drops downwardly upon the ear 31 of the lever 29 and, consequently, prevents reciprocation of the pawl 30, as it holds the shaft 24 in its extreme position, and prevents rocking of such shaft as it has moved the arm 23 (see Figure 4) out of the range of the plunger 26. Consequently, after the latch

is tripped, the counting mechanism or automatic mechanism is thrown out of operation.

The means for initiating the operation of the automatic mechanism is controlled by the charging bucket and such mechanism is designed to come into operation when the charging bucket is rocked into charge delivering position. This result is accomplished by providing a lifting or starting cam 41 which operates upon the lower side of the lever 38 and is adapted to rock it into the position shown in full lines in Figure 3 when the plunger 42 is moved inwardly. This plunger is spring urged outwardly by means of the spring 43 and is carried in suitable guides 44 mounted upon the wall 19. The outer end of the plunger is provided with a roller 45 adapted to be struck by one of the arms 46 of the charging bucket when the charging bucket is in charge delivering or elevated position, as shown in Figure 1. The inner end of the plunger 42 strikes the lower tail of the cam 41 and rocks the cam into the position shown in Figure 3. A pin 46 is preferably provided for limiting the motion of the cam 41.

The operation of the apparatus is as follows:

When the charging bucket is rocked into vertical position it passes the plunger 42 inwardly and rocks the cam 41 into the position shown in Figure 3, thus lifting the lever 38 and permitting the catch 12 to drop into the notch 11 of the locking disc. The step by step or ratchet mechanism is thus rendered effective and, consequently, the ratchet wheel 34 is stepped one notch for each revolution of the mixing drum. This rotates the cam 36 and holds the lever 38 and consequently the latch tripping lever 40, in the position shown in Figures 1 and 3. The latch 12 thus remains in the notch of the disc 9 (see Figure 1) and prevents dumping of the mixing drum. The cam rapidly raises and holds the lever 38, as stated, against rocking motion. However, after the ratchet wheel has completed one revolution, the lever 38 suddenly drops downwardly, rocking in a clockwise direction about its pivotal axis. This causes the tripping arm 40 to engage the portion 12' of the latch and release the latch, thus permitting dumping of the mixing drum. At the same time, this downward rocking of the lever holds the lever 29 in its rearmost position and prevents further actuation of the ratchet mechanism.

It is to be noted particularly that although the invention has been illustrated as relating to a tilting mixing drum, it obviously is equally applicable to other types of mixing drums provided that the mechanism controls the locking of the material discharging portion of the apparatus, and it is accordingly to be understood that the invention is to be interpreted as including this type of drum as well as the one illustrated.

It will be seen, therefore, that a very practical counting or automatic device has been provided which is actuated from the rotating mixing drum and which releases the latch after a predetermined number of revolutions of the mixing drum.

It will be seen further that the automatic device is rendered inoperative when the latch is raised, as described above, and is again thrown into operation when the charging bucket delivers a charge to the mixing drum.

It will be seen further that the device is of simple construction and may be easily produced and is substantially fool-proof.

15 Although the invention has been described in considerable detail, such description is intended as illustrative rather than limiting as the invention may be variously embodied and as the scope of such invention is to be determined as claimed.

I claim:

1. A concrete mixer comprising a frame, a revolute mixing drum pivotally carried by said frame, latching mechanism temporarily restraining said drum against tilting motion, a charging bucket, means for elevating said bucket to deliver a charge to said drum, a cam carried by said drum, a ratchet wheel and pawl actuated from said cam, a second cam carried by said ratchet wheel, and means actuated by said second cam for tripping said latch after said drum has executed a predetermined number of revolutions.

2. A concrete mixer comprising a frame, a revolute mixing drum pivotally carried by said frame, latching mechanism temporarily restraining said drum against tilting motion, a charging bucket, means for elevating said bucket to deliver a charge to said drum, a cam carried by said drum, a ratchet wheel and pawl actuated from said cam, a second cam carried by said ratchet wheel, and means actuated by said second cam for tripping said latch after said drum has executed a predetermined number of revolutions, and means for initiating the operation of said ratchet and pawl mechanism, said means being thrown into operation by the elevation of said charging bucket.

50 3. A concrete mixer comprising a frame, a revolute drum tiltingly carried by said frame and provided with a locking disc having a notch therein, a latch adapted to drop into said notch, automatic mechanism carried by said frame and comprising a ratchet wheel, a reciprocating pawl cooperating therewith, a cam carried by said drum, means positioned in the path of movement of said cam for op-

erating said pawl, a second cam driven from said ratchet wheel, latch releasing means operated from said second cam, a projecting plunger adapted to be moved inwardly by said charging bucket when said charging bucket is moved to charge delivering position, and means actuated by said projecting plunger for initiating the operation of said automatic mechanism.

4. A concrete mixer comprising a frame, a revolute drum tiltingly mounted within said frame and having a latching disc provided with a notch, a latch adapted to drop into said notch to temporarily restrain said drum from tilting motion, a cam carried by said drum, automatic mechanism carried by said frame and including a ratchet wheel, a pawl cooperating therewith, a plunger for actuating said pawl arranged in the path of movement of said cam, a second cam rigid with said ratchet wheel, a lever controlled by said second cam and connected to said pawl to render said pawl inoperative when said lever is released by said cam, latch tripping mechanism operated from said lever and adapted to raise said latch from said notch, a third cam for moving said lever into pawl releasing position, a plunger cooperating with said third cam, a charging bucket, means for elevating said charging bucket, said charging bucket having a portion positioned in line with said plunger and adapted to drive said plunger inwardly to actuate said third cam.

5. In a mixing machine, the combination of a frame, a mixing drum carried by said frame, discharge means for discharging material from said drum, a latch for preventing the discharging means from operating, and automatic means for releasing said latch after said drum has executed a predetermined number of revolutions.

6. In a mixing machine, the combination of a frame, a mixing drum carried thereby, means for discharging material from said drum, a latch for holding said discharging means against operation, a charging bucket for delivering a charge to said drum, automatic mechanism for releasing said latch after said drum has executed a predetermined number of revolutions, and means for initiating the operation of said automatic mechanism when said bucket is moved to charging position.

In testimony that I claim the foregoing I have hereunto set my hand at Port Washington, in the county of Ozaukee and State of Wisconsin.

MICHAEL GILSON.
